US0D1096017S

(12) **United States Design Patent** (10) **Patent No.:** **US D1,096,017 S**
(45) **Date of Patent:** **** Sep. 30, 2025**

(54) **LITTER BOX**

(71) Applicant: **Shenzhen Panshan Trading Co., Ltd.**,
Shenzhen (CN)

(72) Inventor: **Xiaofei Liao**, Shenzhen (CN)

(73) Assignee: **Shenzhen Panshan Trading Co., Ltd.**,
Shenzhen (CN)

(**) Term: **15 Years**

(21) Appl. No.: **29/999,629**

(22) Filed: **Apr. 16, 2025**

(51) **LOC (15) Cl.** **30-11**

(52) **U.S. Cl.**

USPC **D30/161**

(58) **Field of Classification Search**

USPC D30/108, 109, 112, 161, 162

CPC .. A01K 1/0107; A01K 1/0114; A01K 1/0117;

A01K 1/0125

(57) **CLAIM**

The ornamental design for a litter box, as shown and described.

DESCRIPTION

FIG. 1 is a top, front, left side perspective view of a litter box, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 1;

FIG. 10 is an enlarged view of the portion 10 in FIG. 1;

FIG. 11 is an enlarged view of the portion 11 in FIG. 1; and,

FIG. 12 is an enlarged view of the portion 12 in FIG. 2.

The evenly dotted broken lines illustrate portions of the litter box and form no part of the claimed design. The dot-dash-dot broken lines define the boundaries of enlarged views and form no part of the claimed design.

1 Claim, 12 Drawing Sheets
